FRANZ LÖSEL, OF BRUNN, CZECHOSLOVAKIA.

ELASTIC-FLUID TURBINE.

Application filed August 26, 1924. Serial No. 734,355.

To all whom it may concern:

Be it known that I, FRANZ LÖSEL, a citizen of Czechoslovakia, residing at Brunn, Czechoslovakia, have invented certain new and useful Improvements in Elastic-Fluid Turbines, of which the following is a specification.

This invention relates to turbines of the elastic fluid type.

10 The object of the invention generally stated is a turbine having higher thermodynamic efficiency than prior known turbines, and particularly a high pressure turbine unit whose low pressure elements possess a novel and improved form of blading in which specially shaped stationary and rotating blades are combined in a novel manner whereby the working efficiency of the turbine is substantially increased.

20 With the steam pressures ordinarily heretofore used it is possible by superheating to the required degree before admission to maintain the steam above the saturation point substantially throughout the greater part of the turbine so that the saturation point occurs very late or only in the last stages, but with the higher admission pressures being used, the greater part of the low pressure end of the turbine is compelled to 25 work with wet steam unless reheating of the working steam is resorted to. Resuperheating or reheating of the steam is complicated and usually uneconomically effected and therefore in most cases is impracticable. Undue wetness of the steam in the low pressure end of the turbine cannot be avoided with the higher pressures by superheating before admission because superheating cannot be carried at present beyond 450-500° C. with safety. As an example, with steam turbines of admission pressures of 30 atmospheres the steam reaches the saturation point at about 2 atmospheres, and accordingly the whole low pressure part of the turbine working under 30 pressure of 2 atmospheres is compelled to function with wet steam which becomes wetter as the vacuum pressure is reached. The water content of the wet steam tends to lag behind the expanding steam and escapes out of the guide canals with both a diminished velocity and a different direction with reference to the velocity and direction of the steam flow. This lagging water content

60 thrusts thereon, and otherwise impairs the expansive working and efficiency of the steam conveying it. Moreover it is found that an undue water content in the wet steam zone has a deteriorating and injurious influence on the guide blades themselves, especially if of the usual and ordinary construction, and particularly on the portions of the blades near the periphery of the turbines due to the tendency of the fine water drops or contents suspended in the flowing steam to be driven towards the circumference of the rotating parts by centrifugal force.

65 I have found that these objectionable influences may be reduced by properly proportioning the exit angles of the stationary nozzles with reference to the entrance angles of the rotating blades, as for example by 70 diminishing the exit angles of those parts of the stationary blades which guide the wet portions of the steam. The entrance angles of the rotating blades may be correspondingly changed to assist in avoiding the objectionable influences of the water content, and this is preferably effected by rounding the entrance edges of the rotating blades 75 corresponding to the altered exit angles of the stationary blades. The altered angles 80 of the stationary and rotating blades accommodate the functioning of the turbine to the wet steam. Preferably also the stationary guide nozzle chambers are subdivided radially to reduce turbulence losses 85 and to form an interior chamber for the dryer working steam and an exterior circumferential chamber into which the wet steam tends to flow.

90 For a better understanding of the invention, reference may be had to the accompanying drawings forming a part of this application, wherein:

Figs. 1 and 2 are explanatory diagrams, Figs. 3 and 4 are perspective views of the 100 stationary and rotating blades respectively embodying my invention, and

Fig. 5 is a diagrammatic plan view of the stationary and rotating blades.

105 Referring to Fig. 1 illustrating a velocity diagram, v represents the absolute velocity of the steam, u the circumferential velocity and w is the resulting relative exit velocity of the steam. The water part of the steam which tends to lag behind the steam is represented by v' which indicates the absolute velocity of the water content and, since the

55 tends therefore to strike the blades in a manner to exert braking and retarding

peripheral velocity is the same for both the steam and water contents there is a relative exit velocity w' of the water part which differs from the relative velocity w of the steam 5 in both quantity and direction, showing that the water part does not in the ordinary forms of blading enter the rotating nozzle canals in a thrustless manner, but tends rather to strike the blade back and brake or 10 retard the rotation. According to the present invention these objectionable influences are reduced or substantially removed by diminishing the exit angles of the stationary blades with reference to the rotating blades 15 in a radial direction towards the outer circumference in a manner to alter the water flow direction sufficiently to avoid the thrusts upon the back of the blades. Preferably also the corresponding entrance angles of the rotating blades are correspondingly altered, as 20 by gradually rounding the entrance edges thereof in a radial direction towards the circumference.

Referring to Figs. 3, 4, and 5 of the drawings showing an embodiment of my invention, the stationary guide blades a are observed to have an exit angle β at their extreme outer ends radially of the turbine near the circumference of the wheel and an angle 25 α which is substantially larger than the angle β at their inner ends, the angles intermediate the ends varying between the angles β and α in accordance with the demands of practice. Preferably the exit angles should gradually 30 and progressively decrease from the angle α at the inner ends of the blades to the exit angle β at the extreme outer ends. This may be effected by giving to the blades a a distorted or twisted form from the lower ends 35 to their outer ends so as to gradually decrease the exit angles toward the circumference. The vector diagram of Fig. 1 may represent the velocities as to dimensions and directions at the inner ends of the blades, 40 where v is the velocity (absolute) of the steam, v' is the absolute water velocity, u' is the circumferential velocity, w is the relative steam velocity (dotted lines) and w' is the relative water velocity (dotted lines). 45 With the same exit angle alpha (α) at the outer ends of the blades, the relative velocities of the steam and water contacts are represented by the full lines w and w' respectively, the circumferential velocity u at the outer ends being larger than u' . The divergence of the water velocity line w' is observed to increase as the circumferential velocity increases radially outward, while 50 the wet steam, due to centrifugal force, tends to flow outwardly, leaving the dryer steam in the innermost parts of the guide nozzle chambers. The objectionable influences of the wet steam are therefore more pronounced in the outermost portions of the 55 guide nozzles, the construction exhibited in

Figs. 3-5 obviates to a substantial degree these objections in that the divergence of the water velocity w' is gradually decreased in the outward radial direction. Fig. 2 may be used to represent the directions of velocities at the outer ends of the blades embodying my invention, where the exit angle has been reduced from alpha (α) of Fig. 1 to beta (β). The relative steam and water velocities are represented by w and w' respectively, 70 and the reduction of divergence of w' is indicated by the angle phi prime (ϕ') which is observed to be substantially smaller than the angle phi (ϕ) of Fig. 1. As above indicated, the intermediate exit angles vary between alpha and beta with corresponding variations in the other directional angles. In Fig. 2 the direction angle of the relative velocities w and w' is observed to be smaller than the direction angle indicated in Fig. 1, and accordingly the objectionable influences of the water content are thereby substantially reduced particularly in the outer zone of the blades, which works with the wetter steam. 75 In my construction it is evident that even though the water content does lag behind the steam, it does not brake the blade rotation but on the contrary strikes the working side of the rotating blades to do work therein. The performance is still further improved 80 by altering the entrance angles of the rotating blades also, for example, as shown in Fig. 5 in which the angles α' and β' indicate that the rotating blade entrance edge angles are gradually increased radially of the turbine 85 towards the outer circumference in correspondence with the alteration of the exit angles of the stationary blading. Such a result may be effected, for example, by rounding the rotating blade entrance edges from a 90 distinctly sharp edge at the inner ends to a substantially rounded edge at their outer ends, this rounding of the blade entrance edges of the blades b being gradually increased corresponding to the gradual change 95 in the exit angle of the stationary guide blades a . This rounding of the entrance edges of the blade b is indicated at b' , the comparatively sharp inner edge being indicated by b^2 . The rounding of the entrance 100 edges of the blades b cooperates with the reduced exit angles of the stationary blades in eliminating the objectionable influences of the water content of the wet steam and particularly in that it reduces the injurious and 105 destructive influences of the water content upon the rotating blades.

It is desirable to separate the wetter outer zone of the blades from the inner zone in order to minimize the turbulent or whirling 115 losses due to the tendency of the steam to be whirled outwardly caused by the changing construction of both the stationary and rotating blades. For this purpose I have divided the stationary blades into 120

inner and outer zones or chambers which may be accomplished in any suitable manner, as for example by the partitions suitably secured between the blades. The 5 wet or heavier steam tends to be thrown outwardly by centrifugal force and therefore the outer zone or chambers of the guide nozzles formed by the partitions contain the steam with larger water contents, the dryer 10 and lighter steam flowing through the inner chambers.

The gradually diminishing exit angles of the stationary guide nozzles and the gradually altered entrance angles of the rotating blades function efficiently with the wet steam, the angles being such that the lagging water content strikes the rotating blades in a manner to perform work and not brake or retard the rotation. The 15 rounded entrance edges of the rotating blades also function to prevent injury by the impact of the wet steam, and this method of altering the angles is simple and economical.

20 Having thus described my invention what I desire to claim and protect by Letters Patent is:

1. A steam turbine in which the low pressure or wet zone stationary blades are 25 formed with smaller exit angles towards the outer circumference of the turbine and in which the entrance edges of the rotating blades which function with the aforesaid stationary blades are provided with 30 varying entrance angles from their innermost ends to their outermost ends.

2. A steam turbine in which the low pressure or wet zone stationary blades are 35 formed with decreasing exit angles towards the outer circumference of the turbine thereof and in which the entrance edges of the rotating blades are gradually rounded towards the circumference corresponding to 40 the alteration of exit angle of the stationary blading.

3. A turbine of the character set forth 45 in claim 1 wherein the stationary guide blades have a distorted or twisted formation to give the varying exit angle.

50 4. A steam turbine in which the rotating blades in the wet steam zone have entrance edge angles which are gradually increased from their innermost ends to their outer-

most ends for the purpose set forth, and in which the stationary blades functioning 55 with the aforesaid rotating blades are formed so that the exit edge angles at different points therealong vary to correspond with the changes in the entrance edge angles of the rotating blades.

5. A turbine of the character set forth in claim 1 in which the stationary canals are divided into at least two chambers in a radial direction for the purpose set forth.

6. A steam turbine in which the low pressure or wet zone stationary blades are 60 formed with exit angles decreasing towards the outer circumference of the turbine and in which the entrance edge angles of the rotating blades are gradually increased towards the outer circumference in correspondence with the alteration of the exit angles of the stationary blading, for the purpose set forth.

7. A steam turbine in which the low pressure or wet zone stationary blades are 65 formed with exit angles decreasing towards the outer circumference of the turbine and in which the entrance edges of the rotating blades are gradually rounded and their 70 entrance edge angles gradually increased towards the outer circumference in correspondence with the alteration of the exit angles of the stationary blading, for the purpose set forth.

8. A steam turbine in which the low pressure or wet zone stationary blades are 75 formed with exit angles decreasing towards the outer circumference of the turbine and the stationary canals between said stationary blades are divided into at least two chambers in a radial direction, and in which the entrance edges of the rotating blades are gradually rounded and their 80 entrance edge angles are gradually increased towards the outer circumference in correspondence with the alteration of the exit angles of the stationary blading, for the purpose set forth.

90 In testimony whereof, I have signed my name to this specification.
